UNITED STATES PATENT OFFICE.

LEVI M. HAWES, OF HAMPTON FALLS, NEW HAMPSHIRE.

MOWING AND REAPING MACHINE.

SPECIFICATION forming part of Letters Patent No. 281,872, dated July 24, 1883.

Application filed November 13, 1882. (No model.)

To all whom it may concern:

Be it known that I, LEVI M. HAWES, a citizen of the United States, residing at Hampton Falls, in the county of Rockingham and State of New Hampshire, have invented certain new and useful Improvements in Mowing Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to improvements in mowing and reaping machines; and it consists of knives with four cutting-edges, two cutter-bars, which are combined with machinery, and carrying means.

20 From the following description and claims my invention will be fully understood.

Referring to the drawings, Figure 1 is a plan view of my machine; Fig. 2, a section view of the two driving-wheels and the chain-belt wheel between them, on line x x , Fig. 1; Fig. 3, an end view of the hub of the chain-belt wheel. Fig. 4 is a similar view of the sleeves that are used on the hub of the said wheel; Fig. 5, an elevation section view of the machine; Fig. 6, a plan section view of the two finger-bars, two knife-wheels, and gearing. Fig. 7 is an elevation view of the same, except the bars; Fig. 8, an end view of the iron or steel plate before it is bent into the 35 finger-bar, as shown by same view, Fig. 9. Fig. 10 is a detached section view of the finger-bar, fingers, and knives; Fig. 11, an end view of the finger-bar with fingers attached; Fig. 12, a detached plan view of the chain of 40 four-edged cutting-knives; Fig. 13, an edge view of the same.

The two finger-bars A^5 A^5 are rigidly combined in V form. I prefer the angle to be about one hundred degrees. In the outer end 45 of each of the said finger-bars is fixed in the usual manner one sprocket or knife wheel, B^6 or B^7 , which, with two similar wheels, B^8 , Fig. 6, at the junction of the two finger-bars, carry two endless chains, Fig. 10, of four-edged cutting-knives, A^2 , Fig. 12. Motion is 50 imparted to the said knife-chains by the two driving-wheels B^2 B^3 , Fig. 1, which are rigidly

fixed on axle C. On said axle, between said wheels, is the sprocket or chain-belt wheel B^4 , which is connected with said driving-wheels 55 by the sleeves D D' , Fig. 2. The chain belt E passes from wheel B^4 to sprocket-wheel B^5 , this wheel B^5 being connected by a double set of shafting, F F, and beveled gearing F' F' to the knife-wheels B B' , which, with the knife-wheels B^6 B^7 in the outer ends of the finger-bars, carry the knife-chains, as before stated. The two sleeves D D' are provided with teeth E', Fig. 4, on the outer end of each, which engage in corresponding spaces in the hubs of 60 the driving-wheels B^2 B^3 . The sleeves are held engaged with the driving-wheels by means of the thrust-springs D^2 D^3 , and may be disengaged, at the pleasure of the driver in seat G, by drawing toward him the hand-lever G', 70 which is connected to the sleeve-bars H H' by the rod G'. These bars, with end pieces, H' H^3 H^4 , and center piece, H ^{2} , form the combined sleeve-bars. (See dotted lines in Fig. 1.) They are thus pressed against the sleeve-shoulders D^4 D^5 , disengaging the sleeves from the driving-wheels B^2 B^3 , and also arresting the motion of chain-belt wheel B^4 by acting as a 75 brake on the shoulders D^4 D^5 . The hub of the wheel B^4 is provided with projections D^6 D^7 , 80 Fig. 3, which enter into spaces D^8 D^9 , Fig. 4, in the sleeves.

The cutting-knives A^2 are nearly octagonal in form, each knife having four cutting-edges, the bevel on each edge being on the upper 85 side of the knife when at work. Said knives and links A^3 are riveted together, except where the two ends of a chain are connected. These ends are attached by a screw or otherwise, so as to be readily separated for the 90 purpose of reversing the chain or grinding the knives. The knife-wheels at the outer ends of the finger-bars and those at the base are similarly constructed, having a deep groove and recesses in their peripheries for the reception of one side of the knives, and two rows of teeth, C' C', which enter in between the knives, and upon which the sides of the links impinge as the said wheels revolve.

A ^{4} , Fig. 8, represents the form of the iron or 95 steel plate before it is bent and formed into a finger-bar. (See A ^{5} , Fig. 9.)

In Figs. 10 and 11 are shown plan and end views of the manner of attaching the fingers

A^6 to the finger-bar A^5 , and also the peculiar form, and the angle of the fingers to the finger-bar, which is about forty-five degrees. The prongs of the bifurcated shank are secured to 5 the finger-bar at different points to obtain permanence and other apparent advantages. The fingers are longer than those used in ordinary machines, and are placed closer together on the finger-bar. This arrangement, 10 taken in connection with continued motion of the knives and the powerful draw cut given them, enables this machine to cut grass or grain with much power.

The two finger-bars A^5 A^5 are rigidly fixed 15 or inserted into sockets in the base or inner shoe, I, the two bars being at an angle of about one hundred degrees, and in length sufficient to cut a swath of grass or grain ten or twelve feet in width, or even wider. The braces I^1 I^2 20 strengthen the finger-bars. The small trucks I^3 I^4 carry the weight of that part of the machine, ordinary shoes being at the extreme ends of the finger-bars. The base I of the finger-bars is attached by a hinge or joint, I^5 , 25 to the swivel-joint j , which is connected with the axle C by the bars f^4 f^6 , by means of which the finger-bars are held in position and adapted to the ground-surface.

In the rear of the driving-wheels B^2 B^3 , and 30 attached to the axle C, is a frame, k k' , on carrying-wheels a a' and a folding axle, b b' , to which the horses are attached by the drag-bars c c' and shafts c^2 c^3 . The driver can, by means of the roller d , which is provided with 35 a ratchet, d' , and hand-lever d^2 , take up or let out the chain belt e , which passes to the standards f and f' , the latter standard being set in the base I of the finger-bars. In this manner the finger-bar can be raised or lowered at pleasure.

40 In passing through narrow gates or on narrow roads, the rods g g' g^2 g^3 may be removed, and the carrying-wheels a a' and the axle b b' , by means of the four hinge-joints i i' i^2 i^3 , may be folded back to the short axle h , which 45 change is shown by dotted lines. The folding axle may be attached to the short axle by bolts and keys or otherwise. The finger-bars A^5 A^5 and connections with axle C may be folded and elevated over the driving-wheels 50 for transportation. By means of belt-chain e and standard f' , the finger-bars and base may be first brought to an upright position over the hinge I^5 and supported by the bars j' j^2 . When in this position, the lever d^2 on the platform d^3 may then be used to take up the belt-chain e , which is attached to the top of standards f f' by means of a cross-bar. They, with the braces f^2 f^3 and the bars f^4 f^5 f^6 , make the frame f^7 . This frame raises the finger-bars, 55 base, and swivel-joint upward until the bars f^5 f^6 are perpendicular, and the standards f f' are lying horizontally on the frame-bars k k' . The finger-bars are now directly over the driving-wheels, and may be turned aside into any 60 desired position by means of the swivel-joint j . By means of the drag-bars c c' , the shafts c^2 c^3 are placed at the extreme ends of the fold-

ing axle b b' , thus enabling the driver and horses to guide and turn the machine more easily than by any other method. The teeth 70 of the sleeves D D' , being cam-shaped, force the sleeves back from the hubs of the driving-wheels when the machine is moved backward. The lips K K' on the hub of belt-wheel B^4 serve to protect the thrust-springs 75 D^2 D^3 . The shafting and gearing, Fig. 6, may be covered by an iron shell.

By using bushing in the two holes of the cutting-knives, the two sides of the links may be rigidly riveted together. By means of the 80 swivel-joint j , either of the finger-bars may be elevated or depressed to suit the surface of the ground or to pass an obstruction. As but one of the four cutting-edges of the knives can be used at the same time, it can be readily 85 seen that the reversible chain of knives is equal to four sickles of the ordinary machines.

What I claim, and desire to secure by Letters Patent, is—

1. The driving-wheels B^2 B^3 and axle C, in 90 combination with the sprocket or belt wheel B^4 , having two sleeves, D D' , provided with teeth to engage the hubs of the driving-wheels B^2 B^3 , the shoulders D^4 D^5 , projections D^6 D^7 , spaces D^8 D^9 , thrust-springs D^2 D^3 , and lips K 95 K' , substantially as and for the purposes set forth.

2. The above-described sprocket or belt wheel B^4 , in combination with the chain belt E, the central sprocket-wheel, B^5 , the single 100 shaft F F , and the double set of bevel-gearing F^1 F^2 , substantially as and for the purposes set forth.

3. In a mower or reaper, the sprocket-wheel B^5 , in combination with the single shaft F F , 105 double set of bevel-gearing F^1 F^2 , knife-wheels B B' , and two chains of knives, substantially as and for the purposes set forth.

4. The above-described blades A^2 and plates A^3 , in combination with sprocket-wheels B 110 B^6 , whereby the four cutting-edges of said blades may be used alternately without separating the blades from the plates or chain, substantially as set forth.

5. The central base or shoe, I, in combination 115 with the finger-bars A^5 A^5 , rigidly attached thereto, substantially as set forth.

6. The central base or shoe, I, provided with truck-wheels I^3 I^4 , in combination with finger-bars A^5 A^5 , substantially as set forth. 120

7. In a mower or reaper, the central hinge-joint, I^5 , in combination with base I, provided with trucks, and the two finger-bars A^5 A^5 , substantially as set forth.

8. The central swivel-joint, j , in combination 125 with the central hinge-joint, I^5 , the base I, and the finger-bars A^5 A^5 , substantially as and for the purposes set forth.

9. The bars j' j^2 , in combination with the base I and finger-bars A^5 A^5 , whereby said base and 130 finger-bars are supported in an upright position prior to being elevated over driving-wheels, substantially as set forth.

10. The roller d , provided with a hand-le-

- ver, d^2 , and ratchet d' , the belt-chain e , the frame f^7 , the axle C, and the standard f' , in combination with the base I, substantially as and for the purposes set forth.
- 5 11. The roller d , provided with a hand-lever, d^2 , and ratchet d' , the belt-chain e , the frame f^7 , and axle C, in combination with the swivel-joint j , the hinge-joint I' , and base I, substantially as and for the purposes set forth.
- 10 12. In a mower or reaper, the axle C, in combination with the frame-bars $k k' f^5 f^6$ and the frame f^7 , substantially as and for the purposes set forth.
13. The sleeve-bars H H', provided with end pieces, $H^2 H^3 H^4$, center piece, H^5 , and rod G^2 , in combination with clutch-sleeves D D', provided with shoulders $D^4 D^5$, and thrust-springs $D^2 D^3$, substantially as and for the purposes set forth.
- 15 14. In a mower or reaper, the axle $b b'$, provided with four hinge-joints, and means whereby the axle may be folded, substantially as and for the purposes set forth.
- 20 15. In a mower or reaper, the folding axle $b b'$, provided with wheels $a a'$, in combination with rods $g g'$, bars $k k' f^5 f^6$, and axle C, substantially as and for the purposes set forth.
- 25 16. In a mower or reaper, the axle $b b'$, having four hinge-joints, and provided with carrying-wheels $a a'$, drag-bars $c c'$, and thills $c^2 c^3$, substantially as and for the purposes set forth.
17. The folding axle $b b'$, provided with carrying-wheels $a a'$, drag-bars $c c'$, and thills $c^2 c^3$, in combination with axle h , substantially as and for the purposes set forth.
18. The rods $g g' g^2 g^3$, in combination with the bars $k k'$, the folding axle $b b'$, and the axle h , substantially as and for the purposes set forth.
19. The alternate axle h , in combination with folding axle $b b'$, carrying-wheels $a a'$, drag-bars $c c'$, and thills $c^2 c^3$, substantially as and for the purposes set forth.
20. The alternate axle h , in combination with folding axle $b b'$, carrying-wheels $a a'$, drag-bars $c c'$, thills $c^2 c^3$, bars $k k'$, and axle C, substantially as and for the purposes set forth.

In testimony whereof I affix my signature in presence of two witnesses.

LEVI MELCHER HAWES.
